UNITED STATES PATENT OFFICE.

MATTHIAS J. KASPAKI, OF CHICAGO, ILLINOIS, ASSIGNOR TO INTERNATIONAL HARVESTER COMPANY, OF CHICAGO, ILLINOIS, A CORPORATION OF NEW JERSEY.

COMBINATION BALLER.

Application filed May 28, 1924. Serial No. 716,353.

This invention relates to twine balling machines of the type employing a reciprocatory twine guiding and polishing member, and particularly to an improved bearing co-operating with said reciprocatory member to enhance and insure its efficient operation.

This reciprocatory member which is substantially vertically disposed and movable in a horizontal plane is, during its operation, constantly subjected to a plurality of forces, to wit, an outward force and a downward force, both of which resolve into a component force acting to slow down the speed of the reciprocatory member, thereby generating considerable heat and in general lowering the efficiency of the entire balling machine.

The objects of this invention are to overcome these forces by providing a novel form of bearing cooperable with the reciprocatory member to facilitate its operation, and in general to improve the operation of balling machines of this type.

The preferred embodiment of the invention is illustrated in the accompanying sheet of drawings, wherein:

Fig. 1 is a front elevational view of a balling machine showing the reciprocatory member and the improved bearing in co-operative position therewith;

Fig. 2 is a front elevation, as viewed from the left in Fig. 1, of the reciprocatory twine guiding and polishing member with the bearing in association therewith;

Fig. 3 is an enlarged sectional view of the reciprocatory member and bearing taken along line 3-3 of Fig. 2 and looking in the direction of the arrows;

Fig. 4 is a front elevation of the bearing; and

Fig. 5 is a detail face view of the twine guiding and polishing member.

The balling machine is in all essential respects like that disclosed in applicant's prior Patent No. 1,452,298 granted April 17, 1923, and comprises a frame 10, the lower half not being shown, at the upper part of which is supported a drive shaft (not shown) carrying a loose pulley 11 and a fast pulley 12 adapted to be driven by a belt 13. In this manner, rotation is imparted to the usual collapsible bobbin winding spindle 14 by a train of gearing (not shown) and to the shaft 15 (see Fig. 2) suitably journaled in the frame of the ma-

chine. The shaft 15 has fixed thereto the cam 16, the peripheral groove of which engages a roller 17 carried at the end of the conventional twine guiding and polishing member, comprising an extension 18, an integral face portion 19 which supports in any conventional manner, as by means of a nut 20, the guiding and polishing member 21, the nut and member being apertured to permit passage of the twine onto the winding spindle 14.

Referring to Fig. 3, it will be seen that this guiding device is carried by a bracket 22 pivoted at 23 to the frame of the machine and, at its opposite end, to the shaft 15. The rear face of the upper end of the bracket 22 has securely bolted thereto, by means of bolts 24, an upwardly extending backing plate 25 terminating at a point just below the aperture in the twine guide and polishing member 21. An upstanding integral lip portion 22' is formed along the forward upper edge of the bracket 22 and spaced from the plate 25 to provide a longitudinally extending channel-like passageway. Extending into this passageway and bolted to the plate 25 by bolts 26 is a longitudinal track member 27 so constructed and arranged as to provide another passageway between its back side and the plate 25. Vertically above this second passageway and carried by the front side of the upper end of the plate 25 is a longitudinally extending strip 28. Abutting the strip 28 and supported on the track member 27 is a novel roller race or bearing member. This member comprises a plate 29 extending into the passageway between the member 27 and plate 25, and carries on its front face a plurality of spaced cylindrical rollers 30 fastened to the plate 29 by horizontally disposed rivets 31. These rollers, as shown, bear upon the track 27. The plate 29 extends upwardly to a point slightly spaced from the strip 28 where it is provided with a right angularly, forwardly extending ledge 32 which supports a plurality of spaced cylindrical rollers 33 arranged on vertically disposed studs 34 carried between the ledge 32 and a capping plate 35. These rollers abut and bear against the strip 28. The face plate 19 of the reciprocatory member bears against the rollers 33 and is provided with two parallel ribs, the upper rib 36 projecting rearwardly under the ledge 32.

and spaced therefrom slightly and bearing down on the upper side of the horizontal rollers 30. The lower rib 37 is shorter and projects into the passageway in back of the lip 22' to prevent accidental displacement of the bearing or face plate.

This roller race, it should be appreciated from the above description, is loosely disposed in its position between the plates 19 and 25. In its sliding movement, responsive to the movement of the reciprocating member of which the plate 19 is a part, it cannot slip out at the ends because the rollers are so proportioned that the extent of rolling movement of the bearing is considerably less than the extent of movement of the plate 19. As a consequence the bearing is held to duty even though it is loose.

In operation the plate 19 is reciprocated by the cam 16 driven from the pulley 12. The twine coming from suitable supply reels (not shown) passes through the reciprocating guide member and onto the winding bobbin 14. As the layers form on the ball being wound, the member 21 polishes the twine. The ball, of course, is increasing in size, and the pivoted bracket 22 gradually is pushed outwardly, and when it strikes the adjustable size control bolt 38, the arm 39 is swung to actuate the belt shifting mechanism 40 to shift the belt from the fast pulley 12 to the loose pulley 11, thereby automatically stopping the machine when a completed ball has been wound. The ball is then removed from the spindle 14, it first being collapsed by the usual foot pedal operated link and associated mechanism 41.

The roller race provides perfect rolling contact for the reciprocating member and all friction is reduced to a minimum. The generation of heat is also pretty well overcome. The rollers 33 take care of all lateral or outward forces while the rollers 30 take care of all downward forces due to the thrust and pull of the cam 16 on the reciprocating member.

Only the preferred embodiment of the invention has been described and it should be understood that changes in form, construction and arrangement of parts may be re-

sorted to without departing from the invention as hereinafter claimed.

What is claimed is:

1. In a balling machine, a pivoted member provided with a back plate, a reciprocating guiding member movable on the member, and a bearing comprising roller races disposed at right angles with respect to each other between the guiding member and plate. 55

2. In a balling machine, a pivoted member provided with a back plate, a track member on the back plate, a reciprocating guiding member movable on the pivoted member, and a bearing including a roller race bearing on the track member on the back 60 plate disposed between the guiding member and the back plate. 65

3. In a balling machine, a pivoted member provided with a back plate, a track member on the back plate, a reciprocating guiding member movable on the pivoted member, and a bearing including a pair of roller races one of which bears on the track member on the back plate and the other forming a bearing between the guiding member and 70 the back plate. 75

4. In a balling machine, a pivoted member provided with a back plate, a reciprocating guiding member movable on the pivoted member, a rib on the guiding member, a track carried by the back plate, and a bearing comprising a first series of rollers and a second series of rollers, the bearing being supported by means of the first series of rollers operable on the track, the guiding 85 member bearing against the second series of rollers and its rib bearing on the first series of rollers. 80

5. In a balling machine, a bearing adapted to be interposed between two members thereof, one of which is movable relatively to the other, said bearing comprising a plate having an extension substantially at right angles thereto, rollers on the plate disposed parallelly with respect to the extension, and 90 rollers on the extension disposed parallelly with respect to the plate. 95

In testimony whereof I affix my signature.

MATHIAS J. KASPAKI.
